CHARLES EHRLICH, OF NEW YORK, N. Y.

END BAR FOR BED-SPRINGS.

1,158,464.

Specification of Letters Patent. Patented Nov. 2, 1915.

Application filed January 6, 1914. Serial No. 810,558.

To all whom it may concern:

Be it known that I, CHARLES EHRLICH, a citizen of the United States, and a resident of New York city, borough of Brooklyn, in the county of Kings and State of New York, have invented certain new and useful Improvements in End Bars for Bed-Springs, of which the following is a specification.

This invention relates to bed springs, particularly to the end bars which clamp the ends thereof.

The principal objects of the present invention are to provide an end bar which securely clamps and holds the end of the spring; which completely incases the raw edge of the spring so as to entirely conceal the ends of the individual strands or wires and holds them in a dust-proof inclosed casing; and which affords a smooth external 20 surface without any projections which are liable to become caught in surrounding objects.

The various further objects and advantages will more fully appear hereinafter and will be particularly pointed out in the claims.

In the drawings illustrating this invention, Figure 1 is a plan view of the improved end bar showing a fragment of the spring 30 extending thereover. Fig. 2 is a plan of the improved end bar showing the sections of the same open during the process of assembling the device. Figs. 3 and 4 are plan views illustrating fragments of the sections 35 comprising the improved end bars. Figs. 5 and 6 are respectively sections taken along line 5—5 and 6—6 of Figs. 3 and 4. Fig. 7 is a detail view illustrating the section corresponding to Fig. 3, with the teeth flat 40 previous to bending over. Fig. 8 is a cross sectional view illustrating the position of parts during the process of assembly. Fig. 9 is a fragmental plan view illustrating a modified form of bar. Fig. 10 is a cross sectional view of the form in Fig. 9, illustrating the parts during the process of assembly.

Referring in detail to Figs. 1 to 8, the end bar consists of two sections 10 and 11 provided with intermeshing portions which 50 grip the end of the spring 12 and clamp the individual strand securely in place. These intermeshing portions consist of a plurality of teeth 13 formed along one edge of the section 10 and corresponding perforations 14 formed along the adjacent edge of the section 11. When the parts are assembled, the

end of the spring 12 is placed over the upturned teeth 13 of the section 10 and the section 11 is then placed over the teeth which pass through the perforations 14. A rod 15 60 may then be placed along the marginal edge of the section 11 adjacent to the teeth 13 as clearly illustrated in Figs. 2 and 8, and the teeth may then be bent over the rod by some suitable means into the position illustrated 65 in full lines in Figs. 2 and 8. If desired, these teeth may be bent over simultaneously with the section 11 as the latter is swung over into the position shown in dotted lines in Fig. 8. The teeth 13 are thus bent about 70 the wire and securely held thereto by the section 11 which is bent thereover. To completely inclose the end of the spring held by the end bar, the section 11 may be formed with extended portions or flaps 16 and 17 75 respectively on the longitudinal and end edges of the section 11. These extensions or flaps are turned over the edges of the section 10 as illustrated in dotted lines in Fig. 1, and thus securely hold the two sections together, as well as form a tight, dust-proof 80 casing for the end of the spring. Preferably the sections of the end bar are formed of sheet metal stampings which may be formed entirely in one stamping operation 85 in which the outline of the sections are formed as well as the teeth or perforations, as the case may be. Preferably, additional perforations may be formed in the sections during the stamping operation, which perforations may be utilized as points of attachment of the end bar to the frame of the 90 spring. Thus, perforation 18 may be formed in the section 10 and perforation 19 formed in the section 11, so disposed as to register 95 over another when the bar is assembled, as previously described.

In the modified form illustrated in Figs. 9 and 10, the rod 15 is omitted and the teeth 13 of the section 10^a are bent over the adjacent edge of the section 11^a. If desired, the flaps 16^a and 17^a may be formed upon the section 10^a containing the teeth instead of the section containing the perforations as in the other form illustrated. 105

It will thus be seen that I have provided an end bar for bed springs which snugly incases the end of the spring and securely holds the same. By the novel disposition of the teeth in the assembled bar in which they are held bent over in place by the opposing section, the unbending of the teeth 110

or the disengagement of the strands of the spring is rendered impossible for all practical purposes. It will be also clear that by reason of the disposition of the teeth which are turned in the direction of the wires of the spring, they may assist further in holding the spring from disengagement from the end bar. Thus, as clearly appears from Figs. 9 and 10, if the teeth are made long enough, their points may directly engage the wires and thus tend to further assist in holding the spring in position. The teeth in all cases entirely fill the perforations when the parts are bent in place and thus render the casing dust-proof at those points. The marginal flaps inclose the other edges of the casing and thus complete the dust-proof inclosure.

Having thus described my invention, I claim as new and desire to secure by Letters Patent:

1. An end bar for bed springs comprising two sections having intermeshing portions, one series of said intermeshing portions passing through the strands of the spring, the opposing section being bent over the first section and inclosing said series of intermeshing portions and holding them from disengagement.
2. An end bar for bed springs comprising two sections having intermeshing portions, one series of said intermeshing portions passing through the strands of the spring, a rod adjacent thereto, the opposing section being bent over said series of intermeshing portions inclosing the latter and holding them against the rod.
3. An end bar for bed springs comprising two sections, one of which is provided with teeth and the other of which is formed with apertures, said teeth being adapted to pass through the mesh of the spring and then through the apertures of the opposing section, said opposing section being bent over to inclose the teeth and hold them securely in place.
4. An end bar for bed springs comprising two sections, one of which is provided with teeth and the other of which is formed with apertures, said teeth being adapted to pass through the mesh of the spring and then through the apertures of the opposing section, a rod adjacent to the teeth, said opposing section being bent over to inclose the teeth and hold the same securely against the rod.
5. An end bar for bed springs comprising

two sections, one of which is formed with marginal teeth and the other with marginal apertures, said teeth of one section being 60 adapted to pass through the mesh of the spring and the other section overlying the first section with the teeth passing through its apertures, the marginal edges containing the teeth and apertures being disposed at the 65 interior of the sections and forming an inclosed interlocking clamp for the end of the spring.

6. In combination with a wire bed spring, of an end bar comprising two sections, one 70 of which has a series of marginal perforations and the other having a series of marginal teeth passing through the perforations and turning in the direction of the free ends of the strands of the spring, said teeth being 75 held by the body of the opposing bar section toward the spring and concealed thereby, and flaps on one of the sections engaging the other section for inclosing the end of the spring.

7. In combination with a wire bed spring, of an end bar comprising two sections, one of which has a series of marginal perforations and the other having a series of marginal teeth passing through the perforations 85 and turning in the direction of the strands of the spring, said perforated section being bent upon the body of the opposing bar section to inclose the teeth and the spring end, and flaps on one of the sections engaging the 90 other section for binding the two sections together, the teeth substantially entirely filling the recesses when the sections are bent into position to clamp the end of the spring.

8. In combination with a bed spring, of 95 an end bar therefor comprising two sections, one of which is formed with marginal perforations and the other with marginal teeth passing through the perforations and disposed between the two sections and inclosed 100 thereby, the teeth filling the recesses to prevent access of foreign matter into the casing formed by the end bar, and flaps for engaging the free marginal edges of the sections along their entire length to completely 105 inclose the end of the spring and to form a dust-proof casing therefor.

Signed at New York city, in the county of New York, and State of New York, this 5th day of December, A. D. 1913.

CHARLES EHRLICH.
